UNITED STATES PATENT OFFICE.

DAVID B. MACKIE, OF LOS ANGELES, CALIFORNIA.

APPARATUS FOR DESTROYING ANIMAL LIFE.

Application filed January 8, 1921. Serial No. 435,892.

To all whom it may concern:

Be it known that I, DAVID B. MACKIE, a citizen of the United States, residing at Los Angeles, county of Los Angeles, and State of California, have invented a new and useful Apparatus for Destroying Animal Life, of which the following is a specification.

My invention relates to apparatus used for the destruction of insect life, bacteria or the like in various fabrics, food products and other merchandise. It is particularly applicable to the treating of food stuffs and to the treating of hides, fabrics and plants of various kinds.

The principal object of the invention is to provide apparatus for destroying insects or bacteria in all such merchandise without injuring the merchandise or without leaving it in such a condition as to make it necessary to afterwards dry or otherwise treat the merchandise.

Further objects and advantages will be made evident hereinafter.

Referring to the drawings which are for illustrative purposes only,

Fig. 1 is a view of an apparatus with the door closed.

Fig. 2 is a similar view with the door open showing a case of merchandise therein, a portion of this case being broken away to show the internal arrangement.

Fig. 3 is a side view of the apparatus shown in Fig. 1 and,

Fig. 4 is a detail of a small portion of the apparatus showing the locking action.

In the embodiment of the invention shown, a shell 11 is provided, this shell being supported on feet 12 from a floor 13. The shell 11 is formed of sheet metal welded or riveted so that it will withstand considerable pressure, this shell being closed at one end as shown at 14 and being open at the other end. Surrounding the opening is a flange 15 forming an integral part of the shell. Formed on the shell are hinge bosses 20 in which an axle or pin 21 is secured. Turning on the axle 21 are arms 22, forming a support which carries a bolt 23 which passes through a cover 24 at its center, and about which this cover may turn. The cover 24 is provided with lugs 25 which project outwardly beyond the edge thereof, and which may be swung into engagement with lugs 26 formed on the flange 15. The lugs 25 and 26 have the form shown in Fig. 4 being wedge shaped so that as the cover is turned in the

direction of the arrow A, the wedging action forces the cover against the end of a flange 15 and tightly closes the interior of the container. For the purpose of so forcing the cover to rotate I provide an extension 30 carrying a pivot pin 31 on which a bolt 32 is secured. Turning on the threaded portion of the bolt 33 is a hand wheel 34. Formed on the flange 15 above and below the projection 30 are two ears 40 which are slotted as shown in Fig. 3 so that the bolt 32 may pass into this slot and the hub of the hand wheel 34 may press against one edge of the ear 40. By placing the bolt 32 in the proper position as shown in Fig. 1 and turning on the hand wheel, the cover may be rotated in the direction A or by loosening the hand wheel 34 and throwing the bolt through an angle 180 degrees so that it engages the upper ear 40, the cover may be rotated in the opposite direction thus releasing the lugs 25 and 26 allowing the door to be opened. The merchandise to be treated may be placed inside the shell 11 on a truck 50, this merchandise being shown in Fig. 2 as a packing case 51 containing cartons 53 in which merchandise of any kind may be placed. A vacuum pump 60 is provided, communicating through a valve 61 with the interior of the container and a receptacle 62 is also provided in which the liquid from which lethal gas is produced may be stored. The interior of the receptacle 62 communicates through a pipe 63 controlled by a valve 64 with the interior of the container. A pipe 65 controlled by a valve 66 also communicates with the interior of the container and a gauge 67 is so connected that it will indicate the vacuum in the container.

The method of operation is as follows:

The merchandise to be treated, such for example as the merchandise in the cartons 53 is placed inside the shell 11 and the door 24 is closed and locked in gas tight relationship with the shell of the flange 15. The valves 64 and 66 are closed. The valve 61 is opened and the pump 60 is started exhausting the air from the interior of the shell 11 to a certain degree. The packing case 51 and the cartons 53 not being air tight, the air is also exhausted from the interior thereof to the same degree. When the exhaustion has reached the desired point as indicated by the gauge 67, the valve 61 is closed and the valve 63 is opened. This allows gas to be taken from the top of the receptacle 62,

this gas being either replaced with air admitted through a pipe 70 controlled by a valve 71 or being spontaneously generated in the receptacle due to the reduction in pressure.

I find that carbon disulphide is an excellent lethal agent for most purposes. When carbon disulphide is used, it is placed in the liquid form in the receptacle 62 and the valve 71 is opened a small amount so that air is drawn through the pipe 70, immersed in the liquid bubbling therethrough and becoming impregnated with carbon disulphide vapor. This mixture of air and vapor passes through the pipe 63 into the interior of the shell 11, being forced into the interior of the packing case 51 and the cartons 53 and being further forced into all the interstices of the merchandise. The merchandise is then allowed to stand with the carbon disulphide vapor permeating it for sixty minutes or in some cases longer, and the valve 64 is again closed. The pump 60 is started and the valve 61 is opened. A second exhaustion of the interior of the cylinder 11 then takes place, the carbon disulphide vapor being drawn out by means of the pump 60 from the interior of the cartons 53 and from the crevices in the merchandise which it is desired to treat. When this exhaustion has reached any desired degree, the valve 66 is opened and air is allowed to enter the container. If it is desired to effect a very complete removal of the carbon disulphide, the valve 66 may then be closed and a second exhaustion may take place. These exhaustions may be repeated to any desired degree.

I claim as my invention:

1. In a container the combination of a shell; a cover fitting tightly over one end of said shell; a support for said cover; means for pivoting said support on said shell; means for pivoting said cover on said support; a series of lugs on said shell; a series of lugs on said cover engaging said lugs on said shell, one of said series being so formed that said cover is forced against said shell when said cover is rotated; a projection on said cover; a pin turning in said projection; a bolt secured to said pin; a hand wheel threaded on said bolt; and ears on said shell above and below said projection, said ears being so formed that either may be engaged by said hand wheel by turning said bolt.

2. In a container the combination of a shell; a cover fitting tightly over one end of said shell; a support; a hinge member fixed with relation to said shell upon which said support is carried and pivoted; means for pivoting said cover on said support; a series of lugs on said shell; a series of lugs on said cover engaging said lugs on said shell, one of said series being so formed that said cover is

forced against said shell when said cover is rotated; a projection on said cover; a pin turning in said projection; a bolt secured to said pin; a hand wheel threaded on said bolt; and ears on said shell above and below said projection, said ears being so formed that either may be engaged by said hand wheel by turning said bolt.

3. In a container the combination of a shell; a cover fitting tightly over one end of said shell; a support for said cover; means for pivoting said support on said shell; a bolt secured in said support upon which said cover is supported and about which it may be rotated; a series of lugs on said shell; a series of lugs on said cover engaging said lugs on said shell, one of said series being so formed that said cover is forced against said shell when said cover is rotated; a projection on said cover; a pin turning in said projection; a bolt secured to said pin; a hand wheel threaded on said bolt; and ears on said shell above and below said projection, said ears being so formed that either may be engaged by said hand wheel by turning said bolt.

4. In a container the combination of a shell; a cover fitting tightly over one end of said shell; a support; a hinge member fixed with relation to said shell upon which said support is carried and pivoted; a bolt secured in said support upon which said cover is supported and about which it may be rotated; a series of lugs on said shell; a series of lugs on said cover engaging said lugs on said shell, one of said series being so formed that said cover is forced against said shell when said cover is rotated; a projection on said cover; a pin turning in said projection; a bolt secured to said pin; a hand wheel threaded on said bolt; and ears on said shell above and below said projection, said ears being so formed that either may be engaged by said hand wheel by turning said bolt.

5. In a container, the combination of: a shell; a cover adapted to fit tightly over one end of said shell; a support for holding said cover in a position in front of said shell, said cover being rotatably attached to said support; cooperating means upon said shell and said cover engageable so as to force said cover against said shell when said cover is rotated in one direction, and disengageable when said cover is rotated in the opposite direction; a projection on said cover; a pin in said projection; a bolt on said pin; a member threaded upon said bolt; and ears on said shell above and below said projection, said ears being so formed that either may be engaged by said member by turning said bolt.

In testimony whereof, I have hereunto set my hand at Los Angeles, California, this 31st day of December, 1920.

DAVID B. MACKIE.
